UNITED STATES PATENT OFFICE.

JOHN G. EBERHARD, OF AKRON, OHIO.

DESIGN FOR A HAME.

SPECIFICATION forming part of Design No. 13,281, dated September 5, 1882.

Application filed July 21, 1882. Term of patent 14 years.

To all whom it may concern:

Be it known that I, JOHN G. EBERHARD, a citizen of the United States, residing at Akron, in the county of Summit and State of Ohio, have invented and produced a new and original Design for Hames, of which the following is a specification, reference being had to the accompanying drawings, forming part thereof.

Figure 1 is a side elevation, and Fig. 2 is a cross-section, these two views being deemed necessary to fully illustrate my design.

The hame is metallic, and the general configuration of it is indicated by the sectional view in the drawings, the cross-section being substantially the same as in what is commonly known as the "T-shaped" railroad-rail. This constitutes the leading feature of my design.

The side or base *c* is to be of a suitable

shape to fit the collar against which it is to rest, leaving the longitudinal depressions *a* on the outer surface of the hame. In this position, with the base side *c* fitting against the collar, the hame has the general appearance to the eye of a T-shaped railroad-rail bent into a suitable form for a hame. 25

I claim—

The design for a hame, herein shown and described, the same consisting of a metallic hame having longitudinal depressions *a*, and being substantially in the form of a T-shaped railroad-rail with the base side *c* fitted to the collar. 30

JOHN G. EBERHARD.
